UNITED STATES PATENT OFFICE

2,620,749

HATCH FRAME AND INSULATION SUPPORTING PAN FOR REFRIGERATOR CARS

Victor E. West, Chicago, Ill., assignor to Standard Railway Equipment Manufacturing Company, Chicago, Ill., a corporation of Delaware

Application July 8, 1950, Serial No. 172,652

6 Claims. (Cl. 105—377)

1

This invention relates to railway refrigerator cars of the end bunker type, and particularly to easily removable means for supporting insulation up against the roof of the car and about the hatch skirt which is also supported in position by said means. Roofs for such cars are usually formed of a plurality of roof sheets which extend from side plate to side plate of the car, with the end roof sheets, which occur directly over the bunkers, having hatch frames integrally formed therein about hatch openings through said roof sheets. This type of roof sheet and integral hatch frame is shown and claimed in application Serial No. 123,758, filed October 26, 1949, now Patent No. 2,565,706, by Alfred L. Thompson and owned by my assignee. A roof sheet having integrally formed hatch frames therein has been found amply strong to support itself in the car roof structure without the use of inside carlines and purlins, heretofore always thought necessary to support the common hatch frame and cover used in an ordinary roof sheet having hatch openings therein. Those inside carlines and purlins heretofore employed furnished ideal conditions for supporting means to hold insulation up under the roof and about the hatch frame. But due to limitations in the amount of material which can be pressed in a roof sheet about a hatch opening to form a hatch frame integrally therewithout without tearing, the inner wall of an integrally formed hatch frame, at present at least, cannot extend much more than a few inches below the general level of the roof. With carlines and purlins omitted, some means must be provided to support a skirt about the hatch opening and the required insulation up under the roof and about the hatch skirt, and it is the principal object of the invention to provide such means.

In application Serial No. 153,843, filed April 1, 1950, owned by my assignee, one means for so supporting the hatch skirt about the hatch opening, and insulation up against the roof sheets, is shown, which is an assembly of various pans, etc. for the purpose. Another object of the invention is to form said supporting means for each hatch skirt of a single sheet of material pressed into a certain form for attachment of the hatch skirt thereto, and arranged to be attached to the ordinary wood side plate along one end and to the ridge purlins extending between the bulkhead header to the steel end of the car at the longitudinal center thereof.

By this construction the support may be easily removed from the inside of the car whenever necessary, which is a further object of the invention.

2

Other objects and advantages of the invention will appear in the further description thereof.

Referring now to the accompanying drawing forming part of this application and wherein like reference characters indicate like parts.

Fig. 1 is a section transversely of the car through one hatch and the upper part of the adjacent side walls of a railway refrigerator car on line 1—1, Fig. 2.

Fig. 2 is a top plan view of Fig. 1 with the roof sheet removed.

Fig. 3 is a section on line 3—3, Fig. 1.

Fig. 4 is a section on line 4—4, Fig. 1.

Since the invention relates to the structure of end bunker railway refrigerator cars, at and around the hatchways, only one-half of an end roof sheet and ceiling structure, which includes a hatch, and the upper part of the car wall will be described, the other half of the roof, etc., being identical.

The end roof sheet, or in other words, the roof sheet adjacent the end of the car, is indicated at 1, one end of which rests upon the usual side plate 2 and is provided with a turned-down flange

25 3 at the end. Between the ridge 4 and eave of the sheet is integrally formed therein an upwardly pressed rectangular embossment comprising upwardly converging side walls 5, downwardly converging inside walls 6, with the upper edges

30 of said walls 5 and 6 being connected by a downwardly inclined shoulder 7 which is of slight inclination so as to form a seat for the gasket of a hatch cover for closing the hatch opening 8. One side of this roof sheet 1 is provided with a down-turned flange 9 which overlaps and rests upon the upper end of the steel end 10 of the car and the other side of said sheet is provided with an upturned flange 11 adapted to abut against a similarly formed flange 12 of the adjacent roof sheet and be overlapped by the seam cap 13, as is

40 common.

The car side walls comprise outside sheathing 15, the upper margin of which underlaps side plate 2, the spaced side posts 16, insulation 17 and inside wood side plate 18 secured indirectly to side posts 16. The end walls are of similar construction, with the exception of vertical posts which are eliminated, the end 10 extending between and being secured to the corner posts of the car.

45 In end bunker refrigerator cars, a bulkhead 20 extends transversely of the car from side to side thereof and spaced from and parallel with end wall 10 and adjacent inner wall of hatch 8. This bulkhead is provided with a header comprising 2 members each having a portion 21—21 disposed vertically and in abutting relation with

50 55

overlapping flanges 22-22 extending laterally in the same direction from upper end of portions 21-21, and with flanges 23-23 extending laterally in opposite directions in the same planes so as to rest upon the top of bulkhead 20. Flanges 23-23 terminate in reflanges 24-24 which abut and overlap the outer surfaces of the upper end of bulkhead 20 and are secured thereto in any desired manner.

At the longitudinal center of the car, directly under ridge 4, a downwardly facing channel-shaped brace 30 is provided extending from the bulkhead header to the steel end and which provides a substantial center brace for said bulkhead. The lower outer corners of the flanges 31 and 32 of said brace are cut away, as clearly shown in Fig. 4, so as to overlap at the inner end flanges 23 and 24 of the bulkhead header and at the outer end the inner end plate 33. The inner end of flanges 31 and 32 are provided with short reflanges 34 and 35 respectively, which are secured in any desired manner to portions 21-21 of the bulkhead header. At the other end of said brace 30, flanges 31-32 are provided with similar reflanges 36-37 respectively, which are secured to the web of a channel 38 which in turn is welded to steel end 10.

The hatch skirt comprises a single sheet of material 40 bent into rectangular form and welded together at the meeting edges. Said hatch skirt is of a size to overlap the inside walls 6 of the hatch frames so that said walls 6 extend downwardly within the upper margins of the hatch skirt.

The upper edge of said hatch skirt 40 is outwardly flared so as to fit the juncture of walls 6 and shoulder 7 of the hatch frame. In the lower margin of each wall of the skirt 40 are formed outwardly pressed embossments 41 for securing thereto the supporting sheet 42. Supporting sheet 42 is formed from a single sheet of material having an opening therein defined by downturned flanges 43, which flanges occur in the same planes as the outer surfaces of embossments 41. Fastening means, such as the bolts 44, secure all embossments to sheet 42. It will be noted that the heads of said bolts lie wholly within the bounding planes of said embossments so as to form no obstruction to materials being loaded through the hatch frame and skirt. The side of said skirt 42 adjacent the side wall of the car is provided with a downturned flange 45, which flange is removably secured in any desired manner to inner side plate 18. The side of said sheet adjacent brace 30 is inclined downwardly and terminates in a flange 46 which is removably secured to flange 31 of said brace 30. That side of said sheet 42 adjacent steel end 10 is provided with downturned flange 47 which is likewise removably secured to inner end plate 33. Also that side of said sheet 42 adjacent the bulkhead header is provided with downturned flange 48, removably secured to one of the flanges 24 of said header.

From the above it will be apparent that said sheet 42 forms an enclosure about and supports the hatch skirt up in position under the hatch frame of the roof sheet 1. The insulation in the roof is also supported by said sheet 42 under the roof sheet 1. Sheet 42 is thus readily removable from the inside of the car whenever necessary without disturbing the roof sheet, which is a decided convenience.

I claim:

1. For use in a railway refrigerator car having a roof sheet provided with a hatch opening, a hatch skirt adapted to lap the margins of said hatch opening and depend therefrom, and an integral hatch skirt supporting sheet having an opening therein, the margins of said last mentioned opening being secured to said hatch skirt, the periphery of said sheet being adapted for attachment to adjacent car parts.

10 2. In a railway refrigerator car having a roof sheet provided with a hatch opening, a steel end, a bulkhead header spaced inwardly from said steel end and a brace extending from said header to said steel end; a hatch skirt lapping the margins of said hatch opening, and an integral hatch skirt supporting sheet having an opening therein, the margins of said last mentioned opening being secured to said hatch skirt, the periphery of said hatch skirt supporting sheet being secured to said bulkhead header and said brace.

15 3. In a railway refrigerator car having a roof sheet provided with a hatch opening, a steel end, a bulkhead header spaced inwardly from said steel end, inner side and end plates, and a brace extending from said header to said steel end; a hatch skirt lapping the margins of said hatch opening, and a hatch skirt supporting sheet having an opening therein, the margins of said last mentioned opening being secured to said hatch skirt, the periphery of said hatch skirt supporting sheet being secured to said inner side and end plates, said bulkhead header and said brace.

20 4. For use in a railway refrigerator car having a roof sheet provided with a hatch opening, a hatch skirt adapted to lap the margins of said hatch opening, and an integral hatch skirt supporting sheet having an opening therein, the margins of said last mentioned opening provided with flanges defining said opening, said flanges being secured to said hatch skirt, the periphery of said sheet being adapted for attachment to adjacent car parts.

25 5. For use in a railway refrigerator car having a roof sheet provided with a hatch opening, a hatch skirt adapted to lap the margins of said hatch opening, and an integral hatch skirt supporting sheet having an opening therein, the margins of said last mentioned opening provided with flanges defining said opening, said flanges being secured to the lower margin of said hatch skirt, the periphery of said sheet being adapted for attachment to adjacent car parts.

30 6. For use in a railway refrigerator car having a roof sheet provided with a hatch opening, a hatch skirt adapted to lap the margins of said hatch opening and having outwardly pressed spaced embossments therein, and a hatch skirt supporting sheet having an opening therein, the margins of said last mentioned opening provided with flanges defining said opening, said flanges being secured to said embossments, the periphery of said sheet being adapted for attachment to adjacent car parts.

VICTOR E. WEST.
